UNITED STATES PATENT OFFICE.

PAUL S. BOSTWICK, OF WOODBINE, IOWA.

VALVE-GEAR.

SPECIFICATION forming part of Letters Patent No. 729,998, dated June 2, 1903.

Application filed June 6, 1902. Serial No. 110,458. (No model.)

To all whom it may concern:

Be it known that I, PAUL S. BOSTWICK, a citizen of the United States, and a resident of Woodbine, in the county of Harrison and State of Iowa, have invented a new and Improved Valve-Gear, of which the following is a full, clear, and exact description.

The invention relates to steam-engines—such, for instance, as shown and described in the application for Letters Patent of the United States No. 105,983, filed by me on May 5, 1902.

The object of the invention is to provide a new and improved valve-gear which is simple and durable in construction, very effective in operation, actuated from the reciprocating cross-head, and arranged to permit minute adjustment of the cut-off mechanism to run the engine as economically as possible.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement as applied. Fig. 2 is a plan view of the same. Fig. 3 is a cross-section of part of the cut-off-adjusting mechanism, the section being on the line 3 3 of Fig. 1. Fig. 4 is a sectional plan view of the improvement as applied, and Fig. 5 is a cross-section of the same on the line 5 5 of Fig. 4.

The engine on which the valve-gear is applied is provided with the cylinder A, in which reciprocates the piston B, connected by the piston-rod C with the cross-head D, having the usual pitman connection with the main shaft of the engine or having a connection with the shaft, such as described in the application for Letters Patent above referred to.

The cylinder A is provided with the usual admission-ports a b and the exhaust-port c, opening into the valve-chamber E, containing a rock-valve F, having cut-out portions d d' at opposite sides, and the said valve-chamber E is connected on opposite sides by ports e e with an admission-chamber G, connected by a port f with the steam-chest or

receiving-chamber H, connected by the pipe I with a boiler or other suitable source of supply.

The stem F' of the rock-valve F is provided at its outer end with a crank-arm F², having its wrist-pin F³ alternately engaged by the spaced shoulders F⁴ F⁵ of a slide F⁶, rigidly connected at one end with the bracket D' of the cross-head D. The other end of the slide F⁶ is formed with an elongated slot F⁷, engaged by a pin F⁸, attached to the cylinder, so as to properly guide the slide in its forward and backward movement with the cross-head D. Now when the cross-head D reciprocates a like movement is given to the slide F⁶, and the spaced shoulders F⁴ F⁵ thereof impart a swinging motion to the crank-arm F², so that the valve F is rocked in the valve-chamber E. Now when the piston B is at the end of its inward stroke, as shown in the drawings, then the cut-out portion d connects the ports a and e with each other to allow live steam to pass into the inner end of the cylinder to push the piston on its outward stroke. The steam in front of the piston passes by way of the port b and cut-out portion d' into the exhaust-port c and the usual exhaust-pipe which carries the exhaust-steam to the outside air or to a condenser, as the case may be. When the piston B nears the end of its outward stroke, then the shoulder F⁵ moves in engagement with the pin F⁸ to impart a rocking motion to the valve F to connect the ports a and c with each other by the cut-out portion d and to connect the port b with the port e', so that live motive agent now passes into the outer end of the cylinder A to push the piston B on its inward stroke.

The amount of motive agent passing from the receiving-chamber H by way of the port f into the admission-chamber G is controlled by a cut-off valve J, having two ports g and g' alternately connecting with the port f on reciprocating the valve J. The latter has its valve-stem J' extending through a suitable stuffing-box to the outside of the chamber H, and the outer end of this valve-stem J' is pivotally connected with a lever K, having an extension K' connected by a link K² with the bracket D' of the cross-head D.

The lever K is slidably engaged by a guide-way L, having a pivot-pin L' engaged by an

arm N extending longitudinally and fulcrumed at N' on the chamber H, (see Fig. 1,) and the said pivot L' is connected by a link O with a hand-lever P under the control of 5 the operator and adapted to be locked in any position to the fixed quadrant Q. Now when the cross-head D reciprocates then the bracket D', by the link K², imparts a swinging motion to the lever K, the latter turning, with its 10 guideway L, on the pivot-pin L', held in position by the arm N and link O. Now this rocking motion of the lever K causes a reciprocating of the stem J' and cut-off valve J to move the ports g g' alternately in register with the 15 port f.

When it is desired to reduce the amount of motive agent passing through the registering ports g f and g' f from the chamber H into the admission-chamber G, then the operator 20 swings the hand-lever P in the direction of the arrow a' (see Fig. 1) to cause the link O to pull on the pivot L', so that the guideway L moves up on the lever K to bring the pivot-pin nearer to the pivot of the valve-stem J', 25 so that the rocking motion of the lever K is diminished, and consequently the travel of the cut-off valve J is reduced to cause the ports g g' to register but partly with the port f. By moving the hand-lever P into a horizontal 30 position in the direction of the arrow a' the pivot-pin L' is brought in transverse alinement with the pivotal connection of the stem J' with the lever K, so that no movement is given to the slide-valve J, and the latter stands then in a closed position—that is, 35 both ports g g' are out of register with the port f.

By the arrangement described the cut-off of the motive agent can be controlled by the 40 operator to the minutest degree to run the engine as economically as possible relative to the consumption of the motive agent.

Having thus described my invention, I claim as new and desire to secure by Letters 45 Patent—

1. In a valve-gear, a valve-chamber, a valve in said chamber and controlling the admission and exhaust ports, means for operating the valve from the cross-head of the engine, 50 a receiving-chamber connected with the motive-agent supply, an admission - chamber communicating with the receiving-chamber and the valve-chamber, a valve controlling the admission of the motive agent from the 55 receiving to the admission chamber, means for operating said valve from the cross-head of the engine, and means under the control of the operator for regulating the throw of the said valve, as set forth.

60 2. In a valve-gear, a steam-chest having a

receiving-chamber connected with the motive-agent supply, a valve-chamber, an admission-chamber between the valve-chamber and receiving-chamber and having a port opening into the said receiving-chamber, and 65 ports on opposite sides and leading to the valve-chamber, a rock-valve in the valve-chamber and having cut-out portions at opposite sides, and a sliding cut-off valve for the port leading to the admission-chamber 70 from the receiving-chamber, as set forth.

3. A valve-gear comprising a steam-chest having a receiving-chamber connected with the motive-agent supply, a valve-chamber, an admission-chamber having a port opening into 75 the said receiving-chamber, ports leading to the valve-chamber, a rock-valve in the said valve-chamber, controlling the admission and exhaust of the motive agent to and from the cylinder, a cut-off valve for the port, leading 80 to the admission-chamber from the receiving-chamber, the said cut-off valve having two spaced ports for alternate connection with the said admission-chamber port, and means for imparting a reciprocating motion to the 85 said cut-off valve from the cross-head of the engine, as set forth.

4. A valve-gear comprising a steam-chest having a receiving-chamber connected with the motive-agent supply, a valve-chamber, an 90 admission-chamber having a port opening into the said receiving-chamber, ports leading to the valve-chamber, a rock-valve in the said valve-chamber, controlling the admission and exhaust of the motive agent to and 95 from the cylinder, a cut-off valve for the port, leading to the admission-chamber from the receiving-chamber, the said cut-off valve having two spaced ports for alternate connection with the said admission - chamber 100 port, means for imparting a reciprocating motion to the said cut-off valve from the cross-head of the engine, and means for regulating the throw of the said cut-off valve, as set forth.

5. A valve-gear provided with a cut-off 105 valve, a lever pivotally connected with the stem of the said cut-off valve, a connection between the said lever and the cross-head of the engine, a guideway slidably engaging the said lever, a pivot carried by the said guideway, an arm engaging the said pivot and having a fixed fulcrum, and a cut-off lever connected with the said pivot, as set forth.

In testimony whereof I have signed my name to this specification in the presence of 115 two subscribing witnesses.
